United States Patent

Des. 239,148

Patented Mar. 16, 1976

239,148

DUAL RAILROAD PASSENGER SEAT

Harry Mendell Smith and Clarence Joel Skinner, Colorado Springs, Colo., assignors to Aircraft Mechanics, Inc., Colorado Springs, Colo.

Filed Jan. 2, 1974, Ser. No. 429,513

Term of patent 14 years

Int. Cl. D6—01

U.S. Cl. D6—48

FIG. 1

FIG. 2

FIG. 4

FIG. 1 is a front elevation of our new design for a dual railroad passenger seat, with the foot stools in different positions;

FIG. 2 is a top plan view thereof;

FIG. 3 is a side view, with the food trays in different positions;

FIG. 4 is a rear view thereof; and

FIG. 5 is a perspective view thereof.

We claim:

The ornamental design for a dual railroad passenger seat, substantially as shown.
